HYDRAULIC POWER TRANSMITTER

James Fraser and Duncan Campbell, Glasgow,
ScotlandApplication May 25, 1931, Serial No. 539,972, and
in Great Britain April 25, 1931

2 Claims. (Cl. 60—54)

This invention relates to an improved hydraulic power transmitter, and is an improvement in or modification of the invention described in our earlier application for Patent No. 533,858 filed 29th April 1931 and has for its object inter alia, to simplify the construction and assembling of the various parts of the transmitter, and the arrangement of ball-bearings for the rotating parts, and also means for indicating the amount of fluid in the gear, all as hereinafter described with reference to the drawing and pointed out in the claims.

In order that our invention may be properly understood and readily carried into effect, we have hereunto appended a sheet of drawings, of which

Figure 1 is a cross sectional elevation of transmitter.

Figure 2 is an end view of Figure 1, looking in the direction of arrow *a*.

According to this invention and referring to the drawing, *C* is the driving-shaft which is carried on radial ball-bearings *T* and *O* at each end of the driving-shaft *C*, the ball-bearings *T* being carried on an end-cap *Q*, and the ball-bearings *O* being supported within a recess *U* formed in the hub *F*¹ of the driven-disc *F*. A stuffing box *V* is provided at the outward end of the driving-shaft *C*, and is suitably attached to the end-cap *Q*.

The central boss of the impeller *B* is suitably keyed to the driving-shaft *C*, but is capable of sliding longitudinally, and it is provided with radial spokes or division-plates *B*¹, which extend within the impeller *B* until they meet the impeller-blades *A*. The impeller-blades *A* form part of a casting *A*¹, which is attached to the impeller *B* by screws *A*², or other convenient means.

The turbine-blades *D*, forming part of a casting *D*¹, are fixed to the driven-disc *F* by means of screws *D*², or other convenient means.

The stationary-blades *G* form part of a casting *G*¹, and are fixed to the cover-plate *G*² by means of a screw *G*³, or otherwise, the casting *G*¹ being suitably fixed to the central-core *R*¹.

The reverse-blades *E* form part of a ring *V*¹, and are suitably fixed to the casting *D*¹ by means of screws *E*¹, or other means.

The central core *R*¹ is provided with a cover-plate *R*² suitably attached thereto by screws *R*³, the centre-piece *R* being also provided with a cover-plate *R*⁴ suitably fixed thereto by screws *R*⁵, or other suitable means, a space *W* being formed between the cover-plates *R*² and *R*⁴, which pro-

vides an inlet to the conduit *M*. *m* is the supply-pipe connected to the space *W*.

The hub *F*¹ runs on radial ball-bearings *X* carried in the casing *I*, and is provided with a thrust-ball-race *Y* carried on a centre-piece *Z*, this thrust-ball-race *Y* taking up the thrust between the impeller *B* and the hub *F*¹.

The driven-shaft *N*, which forms part of the hub *F*¹, is suitably carried in a radial ball-race *b*, and thrust-ball-race *c*, carried in the casing *d*, and end-cap *e*, respectively, a stuffing-box *f* being provided on the end-cap *e*.

The impeller operating fork *J* engages with a collar *g* attached to the impeller *B*, a thrust-ball-race *h* being provided and held in position by a screw-collar *j*.

A gauge glass *k* is provided, and is suitably connected to the top and bottom of the conduit *M* for indicating the quantity of fluid in the gear. The working chamber or conduit *M* may be divided into a number of passages by radial division plates *S*.

In place of, as in our earlier application, using only water for driving the transmission gear, any other fluid may be employed.

n is a pitot-tube which may be placed in any suitable position in conduit *M* for the passage of fluid into the working chamber.

Having now particularly described and ascertained the nature of our said invention and in what manner the same is to be performed, we declare that what we claim is:—

1. In a hydraulic power transmitter, a casing, a driving shaft in one end of the casing, an impeller mounted in the casing, and having impeller blades, the said impeller slidably keyed to the driving shaft, a central core having stationary blades secured to one face thereof and a ring plate carried on the opposite face, a center piece having an internal opening for mounting a second ring plate, the said central core carried in the opening with the ring plates in spaced apart relation for forming an internal chamber, division plates secured to the casing and center piece for holding the same in spaced apart relation to communicate with the internal chamber and the impeller, means for connecting the exterior and the internal chamber to supply a liquid to the impeller, a driven shaft supported in the opposite end of the casing, a disc carried by the driven shaft having secured thereto a set of ahead turbine blades in direct alignment with the impeller blades for the passage of the liquid to rotate the driven shaft in one direction, the said disc having secured thereto a set of reverse blades ar- 110

ranged concentric to the stationary blades, and means for shifting the impeller with the impeller blades into alignment with said stationary and reverse blades for passage of the liquid to drive the driven shaft in the reverse direction.

- 5 2. In a hydraulic power transmitter, a casing, a driving shaft in the casing, an impeller mounted in the casing and having a central boss slidably keyed to the driving shaft and provided with 10 radial division plates, a casting mounted on the outer portion of the impeller and having impeller blades thereon disposed at the outer ends of the radial division plates, a central core having stationary blades secured to one face thereof and 15 a ring plate carried on the opposite face, a center piece having an internal opening for mounting a second ring plate, the said central core carried in the opening with the ring plates in spaced apart relation for forming an internal 20 chamber, division plates secured to the casing

and center piece for holding the same rigid and in spaced apart relation to communicate with the internal chamber and impeller, a conduit to provide a passageway between the exterior and internal chamber to supply a liquid to the impeller, a driven shaft supported in the casing in alignment with said driving shaft, a disc carried by the driven shaft having secured thereto a set of ahead turbine blades to register directly with the impeller blades for the passage of the liquid to rotate the driven shaft in one direction, the said disc having secured thereto a set of reverse blades, arranged concentric to the stationary blades, and means for shifting the impeller with the impeller blades to register with the said stationary and reverse blades for the passage of the liquid to rotate the driven shaft in the reverse direction.
